NEEDLE

Herman I. Lippard, Winston-Salem, N. C.

Application January 28, 1938, Serial No. 187,336

6 Claims. (Cl. 223—102)

The present invention relates to needles and has reference not only to sewing needles but also to needles which are particularly suitable for tagging merchandise.

5 The invention will be described and in its specific aspects will be claimed with particular reference to tagging needles. For not only is this one of the most promising applications of the invention, but it also lends itself admirably for the specific disclosure of the invention such as is required by the patent statutes. Hence, although the invention will be described with considerable detail and particularity and certain specific terms and language will be utilized, it is to be distinctly understood that the present disclosure is illustrative, rather than restrictive, and that no limitations are to be imported which are not required by the language of the claims and the state of the prior art.

20 In my prior patent (Reissue Patent No. 16,926 issued April 10, 1928), I have described a needle provided with a threading slit at the rear of the eye, the needle to one side of the slit being extended beyond the eye to form a rearwardly extending prong which serves not only as a guide for the element to be threaded but also as a lever for opening the threading slit. The needle of my prior patent has had a great amount of commercial success as a tagging needle for merchandise, chiefly because the needle can be threaded and unthreaded with greater ease than had previously been considered possible. However, the needle of my prior patent has the disadvantage that the prong is likely to be broken off when an undue amount of pressure is applied thereto either during the threading operation or while the needle is being pulled through a thick material or seam.

25 The principal object of my invention is to provide a needle which is not as likely to be broken during normal usage as the needle of my prior patent.

A further object is to provide a needle of relatively simple construction which lends itself readily to being manufactured at a relatively small cost on a large commercial scale.

The needle of the present invention is similar to the needle of my prior patent in that it is provided with a threading slit and in that the needle to one side of the slit extends beyond the eye to form a rearwardly extending prong. It differs from the needle of my prior patent in that the prong terminates at its rear or free end in a protuberance. The protuberance may take any one of a large number of different forms. For instance, it may be simply a bent-up or bent-back

portion of the prong, or it may be a thickened portion or a hump near or at the very end of the prong.

As has already been indicated, the inventive concept underlying the invention is capable of being embodied in various mechanical forms. Two of the many possible embodiments are for the purpose of illustration shown in the accompanying drawing, wherein:

Figure 1 is a side elevation of the needle of the first embodiment when the needle is held in horizontal position;

Figures 2, 3 and 4 are fragmentary side elevations on a larger scale, showing the eye or rear end of the needle and also the successive steps in the threading operation; and

Figure 5 is a fragmentary side elevation of the needle of the second embodiment.

Referring to the drawing in greater detail and more particularly to Figure 1 thereof, the numeral 1 denotes the point or front end of the needle, 2 designates the main body portion and 3 designates the rear or eye end of the needle, which may also be termed the head of the needle.

The numeral 4 denotes the eye of the needle and 5 designates the threading slit which is positioned at the rear of the eye. A long slit 6 may be provided at the front end of the eye but it is not wholly indispensable. This slit merely renders it easier to force the thread or cord through the slit 5 into the eye 4, particularly if the element or cord to be threaded is of considerable thickness.

It is to be noted that the eye 4 and slit 5 divide the head 3 of the needle into two spring arms of different lengths, 7 and 8. The spring arm 7 terminates a short distance beyond the slit 5 and is provided with a bevelled end 9 which slopes downwardly to the slit. The spring arm 8 extends rearwardly beyond the slit to form a prong 10 which is bent back toward the eye to form a hooked end 11. The prong 10 is very much shorter than the corresponding prong in the needle of my prior patent, thereby greatly reducing the tendency of the prong to break off when it is subjected to pressure during normal use. The length of the prong beyond the slit 5 need not be much greater than the thickness of the element or cord to be threaded. It is also to be noted that the thickness of the needle at the hooked end 11 is equal to or less than its thickness at the eye of the needle, thereby obviating any tendency of the hook catching in the material as the needle is pulled through.

The needle illustrated in Figure 5 differs from

the one shown in Figures 1 to 4 inclusive in that the free end of the prong 10' instead of being bent back toward the eye of the needle is simply bent up to form the upstanding protuberance 11'.

- 5 The same result may be obtained by soldering or
welding on an additional piece of material to the
end of a straight prong. It is to be noted that
the various parts of Figure 5 are designated by
primed members corresponding to the numbers
10 used in the other figures.

The needle of this invention may be made of any of the materials usually employed for the purpose.

The threading operation is illustrated in Figures 2, 3 and 4, the letter L denoting the loop of the element or cord to be threaded. The needle is held in one hand near the pointed end 1 and the loop L is slipped over the head 3 to a position in front of the eye 4 (see Figure 2). The loop is pulled toward the eye of the needle so that it slides over the spring arm 7 until it slips down onto the extended portion 10 of the spring arm 8 and is stopped or caught by the hook 10 (see Figures 2 and 3). Then the loop is pulled toward the point of the needle, thereby opening the slit 5 sufficiently to cause the loop to enter the eye of the needle (see Figures 3 and 4). The bevelled edge 9 serves to guide the loop to the slit, but it is thought to be clear that it is not absolutely essential that the edge be bevelled.

For greater clearness of understanding, the needle is illustrated as being disposed with its longitudinal axis in a horizontal position and with the shorter spring arm uppermost. It is to be noted, however, that the needle need not be held in any particular position during the threading operation. Hence, no particular degree of care is necessary in threading the needle, and relatively inexperienced operators and persons of poor eyesight can thread the needle without any undue difficulty.

As has already been indicated, the foregoing disclosure and description are merely illustrative and are not intended to be restrictive of the scope of the invention beyond what is required by the language of the claims and the state of the prior art. It is to be distinctly understood that the essential thought and concept which characterize my invention may be combined with other concepts and that the details of the illustrative embodiment may be modified in various ways or replaced by other details without affecting the peculiar results obtained and without departing from the spirit and scope of the invention as defined in the appended claims. As an indication of the possibilities of the invention, it may be stated that the underlying concept may be embodied in both the shedding and non-shedding types of needles.

60 I claim:

60 1. A needle of the type described, said needle having a main body portion terminating in a point at the front end and in a head at the rear end, said head being provided with an eye, 65 and a threading slit at the rear end of the eye,

said eye and slit serving to longitudinally bifurcate the head end into two spring arms, one of said spring arms extending to the rear of the other and being provided with a protuberance at its free end.

2. A needle of the type described, said needle having a main body portion terminating in a point at the front end and in a head at the rear end, said head being provided with an eye and a threading slit at the rear end of said eye, said eye and slit serving to longitudinally bifurcate the head end into two spring arms, one of said spring arms extending to the rear of the other and being provided with a protuberance at its free end, the thickness of the needle to the rear of the eye being no greater than the thickness at the eye.

3. A needle of the type described, said needle having a main body portion terminating in a point at the front end and in a head at the rear end, said head being provided with an eye and a threading slit at the rear end of said eye, said eye and slit serving to longitudinally bifurcate the head end into two spring arms, one of said spring arms extending to the rear of the other and being provided with a hooked end. 20 25

4. A needle of the type described, said needle having a main body portion terminating in a point at the front end and in a head at the rear end, said head being provided with an eye and a threading slit at the rear end of said eye, said eye and slit serving to longitudinally bifurcate the head end into two spring arms, one of said spring arms extending to the rear of the other and being provided with a hooked end, said needle at the hooked end being no greater in thickness than the needle at the eye thereof. 30 35

5. A needle of the class described, said needle having a main body portion terminating in a point at the front end and in a head at the rear end, said head being provided with an eye and a threading slit at the rear end of said eye, said eye and slit serving to longitudinally bifurcate the head end into two spring arms, one of said spring arms extending to the rear of the other and having a surface to guide a thread to the slit, said spring arm being provided at its free end with a protuberance to serve as an end stop for the threading element.

6. A needle of the class described, said needle having a main body portion terminating in a point at the front end and in a head at the rear end, said head being provided with an eye and a threading slit at the rear end of said eye, the eye and the slit being positioned substantially on the longitudinal axis of the needle and serving to longitudinally bifurcate the head end into two spring arms, said spring arms being on opposite sides of the longitudinal axis of the needle, and one of said spring arms being provided at its free end with a protuberance, said protuberance extending to the opposite side of the longitudinal axis of the needle from the spring arm of which it forms a part. 50 55 60
